Primary Examiner — Mitchell I. Siegel*(74) Attorney, Agent, or Firm* — Inventa Capital PLC(57) **CLAIM**

I claim the ornamental design for a climbing frames play equipment, as shown and described.

DESCRIPTION

This is a Continuation in Part Design application that claims priority to a design application Ser. No. 35/500,103 filed on Aug. 3, 2015 and incorporated herewith by reference in its entirety.

FIG. 1 is a front elevational view of a climbing frames play equipment;

FIG. 2 is a side elevational view of a climbing frames play equipment;

FIG. 3 is a perspective view of a climbing frames play equipment;

FIG. 4 is another side elevational view of a climbing frames play equipment;

FIG. 5 is a top view of a climbing frames play equipment;

FIG. 6 is rear elevational view of a climbing frames play equipment; and,

FIG. 7 is a bottom view of a climbing frames play equipment.
